UNITED STATES PATENT OFFICE.

JOHN EDWARDS, OF FLAGSTAFF, ARIZONA.

CONDIMENT-HOLDER.

1,226,759.

Specification of Letters Patent.

Patented May 22, 1917.

Application filed October 7, 1916. Serial No. 124,238.

To all whom it may concern:

Be it known that I, JOHN EDWARDS, a citizen of Norway, residing at Flagstaff, in the county of Coconino and State of Arizona, have invented certain new and useful Improvements in Condiment-Holders, of which the following is a specification.

This invention relates to condiment holders of the kitchen or household type.

10 The object of this invention is to provide means for holding two or more condiments in a single container.

Another object of this invention is to provide means under the control of the operator for discharging two or more condiments independently of each other or simultaneously as desired.

20 A further object is to provide a condiment holder of the class stated which can be conveniently refilled when empty or the contents of which can be readily emptied and other condiments substituted.

Other objects and advantages will be in part apparent and in part described as the 25 description is proceeded with.

In the accompanying drawings:

Figure 1 is a vertical sectional view of my invention;

Fig. 2 is a top plan view with the top 30 open;

Fig. 3 is a detail perspective view of the fixed perforated plate;

Fig. 4 is a detail perspective view of the sliding plate, and

35 Fig. 5 is a detail perspective view of the connecting rod.

Referring more particularly to the drawings, in which like reference numerals refer to similar parts throughout the several 40 views, 1 denotes as a whole a condiment holder or receptacle of any convenient shape and material but preferably constructed of a material that does not rust or corrode. In the embodiment illustrated, the receptacle 1 comprises salt and pepper containers 2 and 3 connected at their upper ends in any suitable and convenient manner to top frame 4, which in turn is secured to and supported by a depending division wall 5. The containers 2 and 3, as best seen in Figs. 1 and 2 45 are fashioned after the conventional octagonal or hexagonal salt or pepper shaker but it is obvious that variously shaped containers may be employed to correspond to any particular shape of division wall and top frame.

Hingedly connected to the top frame as at 6 is a dome shaped cover 7 the curved converging walls of which terminate in the centrally located discharge opening 8. Any 60 suitable snap fastener such as 9 may be employed to lock the cover to the top frame when the former is in closed position.

A plate 10 suitably secured to the cover and lying within the confines of the frame 65 4 rests upon the tops of the containers 2 and 3, the perforated portions 11 of said plate being directly over the open mouths (not shown) of the containers. It will be observed that the longitudinal side edges 70 of the plate 10 are formed with inwardly bent flanges 12 which serve as guide-ways for a pair of perforated sliding plates 13 normally lying in superimposed position upon the perforated portions of plate 10. The 75 perforations 11 and 14 in the respective plates are normally out of alinement but means is provided for moving them into register so that a flow of salt or pepper or of both salt and pepper may be obtained at 80 the will of the operator. This desideratum is effected by the following construction and arrangement of mechanism.

The outer side edges of the sliding plates 13 are formed with upstanding flanges 15 85 having depleted or notched portions as at 16 intermediate their ends to receive a connecting rod 17. The hooked ends 18 of this rod extend through and slightly beyond the notched portions 16 in position to engage 90 the outer face of the flange. A coil spring 19 encircling the rod 17 engages the flanges 15 with its opposite ends thus normally tending to force the plates 14 apart, this movement of the plates being limited by 95 struck up portions or stops 20, formed on the plate 10, adjacent the ends thereof. Substantially U shaped push buttons 21 comprising a head 22 and legs 23 are held upon the ends of the rod 17 partially by reason of 100 their own resiliency and by the offset ends 24 of the legs 23 engaging the inner faces of the stops 20. The offset ends 24 also serve as bearing surfaces for engaging the flanges 15 when the push buttons are 105 actuated.

From the foregoing the operation of the invention will be readily understood but may be briefly described as follows.

When the user desires to obtain either salt 110 or pepper he will push one or the other of the buttons 21, which may be appropriately

labeled, thus causing the corresponding plate 13 to move inwardly against the tension of spring 19 until the perforations 11 and 14 are in register. The receptacle 1 is 5 then inverted and shaken if necessary to produce a flow from the containers 2 and 3 into the dome shaped cover and out through discharge opening 8. If both salt and pepper are desired the user will of course push 10 both buttons. Immediately the buttons are released the spring 19 automatically returns the plates 13 to their normal position.

As many changes could be made in the 15 above construction and many apparently widely different embodiments of my invention, within the scope of the claim constructed without departing from the spirit or scope thereof, it is intended that all matter contained in the accompanying specification and drawings shall be interpreted as 20 illustrative and not in a limiting sense.

Having thus described my invention:

What I claim is:

A condiment holder comprising a plu-

rality of open-mouth containers, a top frame 25 for connecting said containers, a dome-shaped cover hinged to said frame provided with a central discharge opening, a perforated plate carried by said cover overlying the mouths of the containers, a pair of perforated plates having upturned flanges slidably mounted upon said first-mentioned plate, a rod connecting said sliding plates, a coil spring on said rod bearing at its ends against the upturned flanges on said sliding plates and normally holding the plates in position to obstruct the openings in the first-mentioned plate, and push buttons on the opposite ends of said rod and engaging the flanges on the sliding plates for moving same 40 to uncover the openings in the perforated plate.

In testimony whereof I hereby affix my signature.

JOHN EDWARDS.
